RANGE AND POSITION FINDER.

1,407,281.

Specification of Letters Patent. Patented Feb. 21, 1922.

Application filed July 18, 1913. Serial No. 779,740.

(GRANTED UNDER THE PROVISIONS OF THE ACT OF MARCH 3, 1921, 41 STAT. L., 1313.)

To all whom it may concern:

Be it known that I, HEINRICH JUST, residing at Essen-on-the-Ruhr, Germany, a subject of the Emperor of Germany, have invented a certain new and useful Improvement in Range and Position Finders, of which the following is a specification.

This invention relates to range and position finders for indirect laying of guns, in which, when the distance is known between the gun and an observation stand situated at some distance therefrom, a mechanical triangle may be formed, which corresponds to the triangle determined by the relative position of gun, target and observation stand; this being accomplished by first setting the instrument to the range, which the target has relative to the observation stand, and second in azimuth by using the observed direction of an imaginary line drawn between the observation stand and the target.

The object of the present invention is to provide such a range and position finder, wherein the mechanical triangle may be given comparatively large dimensions, without inadmissible proportions of the apparatus, and without reducing the distinctiveness of the graduation.

One embodiment of this invention is illustrated in the accompanying drawings representing a position finder which is intended for a gun having a bed plate graduation, the distance of the observation stand relative to the gun being constant as regards length and direction, and

Figure 1 shows a longitudinal section of the apparatus,

Figure 2 a top plan view of Fig. 1, and

Figure 3 a transverse section on line 3-3 of Fig. 2.

The stand A of the position finder, which is suitably mounted on a wall of a foundation situated near the gun, is provided with a slide B, longitudinally displaceable by means of a screw spindle C. This slide B, has a trunnion b^1 on which a circular cup-shaped graduation disk D is loosely revolvable. On the nave of the graduation disk D is securely fixed an arm d^1 which is provided with a trunnion e^1 journaled in a sleeve E, the axis of which trunnion is parallel to the axis of the trunnion b^1 . The sleeve E is mounted to

slide on a ruler F which is provided with a trunnion G journaled in the bridge a^1 securely mounted at one end of the stand A. The axis of the trunnion G is parallel with the axis of the trunnion b^1 , and is situated in the sliding plane of the latter trunnion. The mechanical triangle is outlined by the axes of the trunnions e^1 , G and b^1 , which triangle corresponds to the triangle determined by gun, target and observation stand; the points of the mechanical triangle are designated by 1, 2 and 3 in Fig. 2, and point 1 corresponds to the gun, point 2 to the target and point 3 to the observation stand. For reading off the length of the side 3^2 , a range scale a^2 is provided which is engraved on the stand A, and an index mark b^3 is engraved on an index b^2 fixed on the slide B. The length of the side 1^2 of the triangle may be ascertained on a graduation f^1 of the ruler F against an edge e^2 of the sleeve E. The zero points of the scales a^2 and f^1 are situated at the end of the graduation nearest the trunnion G.

At the outer edge of the graduation disk D is situated an angle scale d^2 which corresponds to the horizontal angle scale of a stationary, circular graduation on the observation stand, which is not shown in the drawing. The corresponding reading mark b^5 is situated on an index b^4 rigidly secured on the slide B. The position of the zero point of the angle scale d^2 has been selected so that the angle, which the side 3^1 of the triangle, forms with the side 3^2 , when the mark b^5 stands over the zero point, is equal to the angle which an imaginary line, drawn between the observation stand and the gun, forms in the horizontal plane with the zero direction on the stationary, circular graduation of the observation stand. To read the side direction which has to be given to the gun is provided an angle scale d^3 , which is concentric with the angle scale d^2 and provided also on the graduation disk D; and which has the same angular unit as the angle scale of the foundation graduation of the gun. The corresponding reading mark h^1 is situated on a ring sector H, which is slidable in a circular guide-way of the graduation disk D. This sector is provided with internal teeth h^2 meshing with a toothed arc i^1 of a sector J. This sector J surrounds the nave of a spur gear K revolu-

bly mounted on a journal m^1 of an arm M, which in its turn may be revolved around the nave of the graduation disk D.

The arm M is, by means of a link N, connected with the sleeve E, and the ratio has been selected so that the parts E, N, M and d^1 form a link-parallelogram. The spur gear K being mounted to freely revolve relative to the sector J, is in mesh with an internal gear d^4 of the graduation disk D, and carries firmly secured thereon a scale disk K^1 . On this scale disk is engraved an angle scale k^2 , permitting the reading of fractions of the unit which forms the base for the angle scale d^3 . The corresponding reading mark i^3 is situated on a circular flange i^2 of the sector J, which flange partly surrounds the graduation disk K^1 .

The mark i^3 may, within certain limits, be adjusted by means of a self-locking worm P revoluble in two bearings m^2 of the arm M, which worm meshes with a toothed ring i^4 of the sector J, this for the purpose of making the corrections which for instance would be considered necessary for the side deviation caused by the twist from wind or other causes. To read off the adjustments made is provided an angle scale i^5 arranged on the circular flange i^2 , and a mark m^4 situated on the index m^3 carried by one of the two bearings m^2 .

As will be evident from the above, the ring sector H may be secured in several positions relative to the arm M, through the cooperation of the worm gear P, i^4 and the gears i^1 h^2 . The position of the zero point of the scale d^5 has been selected, so that the mark h^1 shows the same angle on the angle scale d^3 as the mark b^5 shows on the angle scale d^2 , when the ring sector H has been adjusted relative to the arm M by turning the worm P, so that the mark m^4 stands opposite the zero point of the correction scale i^5 and when the graduation disk D has been turned simultaneously into such an angular position that the point 1 lies in a straight line with the points 2 and 3. It may then be supposed that the zero direction of the bed plate graduation of the gun is parallel to the zero direction of the circular scale in the observation stand. When the ring sector H is locked to the arm M, and the arm M together with the ring sector H is turned relative to the graduation disk D, the graduation disk K^1 together with the angular scale k^2 , turns then, relative to the mark i^3 of the sector J, actuated by the gears K, d^4 , an angle proportionate to the turning angle of the arm M and the ring sector H. With the ring sector H secured relative to the arm M in that position, wherein the mark m^4 stands opposite the zero point of the correction scale i^5 ; the ratios are selected in such a manner that the mark i^3 indicates the an-

gular distance on the angle scale k^2 in fractions of the unit whereon the angle scale d^3 is based, in every position which the mark h^1 may take relative to the angle scale d^3 , of the mark h^1 from the previous main division line of the angle scale d^3 . The ratio of transmission of the gears i^1 h^2 has moreover been selected to equal the transmission ratio of the gears K d^4 . With the arm M standing still and when, by turning the worm P, the mark h^1 , for the purpose of making corrections, is displaced relative to the angle scale d^3 considered to be stationary, a certain number of fractions of the angular unit; the mark i^3 turns in consequence an angle relative to the scale disk K^1 , also considered stationary, which angle likewise expresses exactly the same number of fractions. The mark i^3 then expresses exactly in fractions of the angular unit in each case against the scale k^2 , the angular distance the mark h^1 has from the previous main division line of the scale d^3 .

To find the elevation and training for the gun to which the described device belongs is accomplished as follows: The range of the target, that is the distance from the observation stand to the latter, is first ascertained and the angle which an imaginary line from the observation stand to the target makes in a horizontal plane with the zero direction of the graduation arc of the observation stand is thereupon read off the graduation arc situated on the observation stand. This amount is transmitted to the gun mount and there adjusted on the device which forms the subject matter of this invention. For this purpose the slide B is displaced so far, by means of turning the screw spindle C until the mark b^3 shows the range on the range scale a^2 , which had been measured on the observation stand. The scale D is thereupon turned by hand until the mark b^5 shows on the angle scale d^2 the horizontal angle observed on the observation stand. The range of the target may thereupon be read off against the edge e^2 of the sleeve E on the scale f^1 of the ruler F, which gives a measure of the range to be given the gun.

As the arm M, being one of the members of the link-parallelogram d^1 , E, N, M, together with the ring sector H, which is locked relative to the arm M by means of the self-locking worm gear P, i^4 , during the turning of the scale disk D, travels parallel to the ruler F, which forms the gun to target side of the triangle; the mark h^1 , situated on the ring sector H, must therefore show the angle on the scale d^3 which the actual gun to target line forms on the ground with the zero line on the bed plate graduation of the gun, when the ring sector H is adjusted to the arm M, in such a manner that the zero point of the correction

scale i^3 registers with the mark m^4 . If now the ring sector H, by means of turning the worm P, is displaced relative to the arm M an amount corresponding to the necessary correction, the mark h^1 will then show directly on the angle scale d^3 the training to be given to the gun with the correction included while the fractions of the angular unit may be read off by means of the mark 10 i^3 on the angle scale k^2 .

It will be evident from the drawing that the circumference which encloses the reading marks of the described device may remain unchanged, even if the scale of the 15 triangle 1, 2, 3, were enlarged. If a greater scale were selected for this triangle, the distinctiveness of the reading off-devices of the apparatus would still remain the same. When the scale is enlarged, only the 20 length of the stand A will be increased. As the stand, however, still may be kept very narrow, the dimensions of the apparatus will therefore, even with comparatively large proportions, remain within permissible 25 limits.

I claim:

1. A range and position finder for guns, comprising a table, a ruler mounted to oscillate thereon, a disk mounted to slide on said 30 table, a link connecting the center of said disk with a journal point on said ruler, said table, ruler, and link producing a mechanical triangle determined by the center of said disk, the axis of oscillation of said ruler, and 35 said journal point; means for adjusting the sides of the mechanical triangle converging at the axis of oscillation of said ruler; and means for adjusting the angles of said mechanical triangle opposite to said sides, comprising longitudinal and angular scales for 40 the range and horizontal position readings respectively, said disk carrying said angular scales and being situated at one of the points of the mechanical triangle distant from said 45 axis of oscillation, and said table and ruler carrying said longitudinal scales, the zero points of said longitudinal scales being situated adjacent the axis of oscillation of said ruler.
2. A range and position finder for guns, comprising a table, a ruler mounted to oscillate thereon, a disk mounted to slide on said 50 table, a link connecting the center of said disk with a journal point on said ruler, said table, ruler, and link producing a mechanical triangle determined by the center of said disk, the axis of oscillation of said ruler, and said journal point; means for adjusting the sides of the mechanical triangle 55 converging at the axis of oscillation of said ruler; and means for adjusting the angles of said mechanical triangle opposite to said sides; said means comprising setting scales on said table and disk respectively for a 60 given range and a given horizontal position 65

adjustment, and measuring scales on said ruler and disk respectively for the range and horizontal position readings for the gun; said disk carrying said angular scales and being situated at one of the points of the 70 mechanical triangle distant from said axis of oscillation, and said table and ruler carrying said longitudinal scales, the zero points of said longitudinal scales being situated adjacent the axis of oscillation of said ruler; 75 said ruler being journaled at one end of said table and being provided with a sleeve, said link being pivoted on said sleeve in said journal point and mounted to revolve in rigid connection with said disk around the 80 axis thereof; a slide mounted in guides on said table and adapted to be adjusted longitudinally in the same vertical plane in which lies the axis of oscillation of said ruler, said disk being revolvably seated on said slide; a 85 horizontal position setting scale and a horizontal position measuring scale, said last named scales being concentrically arranged on said disk.

3. A range calculating instrument for a 90 gun, the instrument having a table, a ruler, a disk, a link connecting the center of the disk with said ruler, and means for adjusting said instrument parts to each other, said ruler being journaled at one end on said 95 table; said means comprising a sleeve on the ruler, said link being pivoted on said sleeve and mounted to revolve around the axis of said disk, a slide mounted in guides on said table and adapted to be adjusted longitudinally in the same vertical plane in which lies the axis of revolution of said ruler, said disk being revolvably seated on said slide; whereby, on mutually adjusting said several 100 parts, a mechanical triangle will be produced, the points of said mechanical triangle being situated respectively in the axis of said disk, in the axis of oscillation of said ruler and in the point of said link.

4. A range calculating instrument for a 110 gun, the instrument having a table, a ruler, a disk, a link connecting the center of the disk with said ruler, and means for adjusting said instrument parts to each other, said ruler being journaled at one end on said 115 table; said means comprising a sleeve on the ruler, said link being pivoted on said sleeve and mounted to revolve around the axis of said disk; a slide mounted in guides on said table and adapted to be adjusted 120 longitudinally in the same plane in which lies the axis of revolution of said ruler, said disk being revolvably seated on said slide, suitable setting scales on the table and the disk respectively for adjusting the finder 125 to range and azimuth as communicated from the observation stand, suitable reading scales on said ruler and disk respectively for range and horizontal position readings for the gun; an index on said slide for said range 130

setting scale, an index on said sleeve for said range reading scale; said horizontal position scales being concentrically arranged on said disk, an index on said slide for said 5 horizontal position setting scale.

5. A range calculating instrument for a gun, the instrument having a table, a ruler, a disk, a link connecting the center of the disk with said ruler, and means for adjusting said instrument parts to each other, said ruler being journaled at one end on said table; said means comprising a sleeve on the ruler, said link being pivoted on said sleeve and mounted to revolve around 10 the axis of said disk; a slide mounted in guides on said table and adapted to be adjusted longitudinally in the same plane in which lies the axis of revolution of said ruler, said disk being revolubly seated on 15 said slide; a range setting scale on said table and an index therefor on said slide; a range reading scale on said ruler and an index therefor on said sleeve; a horizontal setting scale and an index therefor on said slide; a 20 horizontal reading scale; an arm coaxially mounted with said disk, and a connecting member between said arm and said sleeve, forming a link-parallellogram with said 25 sleeve, link and arm, an index controlled by 30 said arm for said horizontal position reading scale.

6. A range calculating instrument for a gun, the instrument having a table, a ruler, a disk, a link connecting the center of the 35 disk with said ruler, and means for adjusting said finder parts to each other, said ruler being journaled at one end on said table; said means comprising a sleeve on the ruler; said link being pivoted on said 40 sleeve and mounted to revolve around the axis of said disk; a slide mounted in guides on said table and adapted to be adjusted longitudinally in the same plane in which lies the axis of revolution of said ruler, said 45 disk being revolubly seated on said slide; a range setting scale on said table and an index therefor on said slide; a range reading scale on said ruler and an index therefor on said sleeve; a horizontal position 50 setting scale and an index therefor on said slide; a horizontal position reading scale; an arm coaxially mounted with said disk, and a connecting member between said arm and said sleeve, forming a link-parallellogram 55 with said sleeve, link and arm, an index con-

trolled by said arm for said horizontal position reading scale; a carrier for said last named index, seated in a concentric groove in said disk, a sector mounted to revolve on said disk coaxially with said arm, gearing 60 connection between said sector and said index carrier and a fine setting gear with suitable graduation between said disk and said sector.

7. A range calculating instrument for a gun, the instrument having a table, a ruler, a disk, a link connecting the center of the disk with said ruler, and means for adjusting said finder parts to each other, said ruler being journaled at one end on said table; 70 said means comprising a sleeve on the ruler, said link being pivoted on said sleeve and mounted to revolve around the axis of said disk; a slide mounted in guides on said table and adapted to be adjusted longitudinally in the same plane in which lies the axis of revolution of said ruler, said disk being revolubly seated on said slide; a range setting scale on said table and an index 75 therefor on said slide; a range reading scale 80 on said ruler and an index therefor on said sleeve; a main horizontal position setting scale and an index therefor on said slide; a main horizontal position reading scale; an arm coaxially mounted with said disk, 85 and a connecting member between said arm and said sleeve, forming a link-parallellogram with said sleeve, link and arm, an index controlled by said arm for said horizontal 90 position reading scale; a carrier for said last named index, seated in a concentric groove in said disk, a sector mounted to revolve on said disk coaxially with said arm, gearing connection between said sector and said index carrier and a fine setting gear with suitable graduation between 95 said disk and said sector; a spur wheel in gearing connection with said disk, said spur wheel being coaxially mounted with said sector and having a scale subdivided into fractions of the unit on said main horizontal 100 position scales, and said sector having an index registering with said fractional scale.

The foregoing specification signed at Bar-
men, Germany, this 27th day of June, 1913. 105

HEINRICH JUST. [L.S.]

In the presence of—

ALBERT NUTER,
JULIUS FESTNER.
